(57) **ABSTRACT**

A cable spool structurally configured for attaching to a surface such as a networking equipment and to support a plurality of fiber optic cables so as to enhance management of fiber optic-cables in high-density applications disclosed. The cable spool comprises an attachment portion and a spool portion. An inner end of the attachment portion is structurally configured to be fixed to the surface. An outer end of the attachment portion is structurally configured to be free standing. The spool portion is moveable relative to the attachment portion between a first position and a second position.

CABLE SPOOL

**CROSS REFERENCE TO RELATED
APPLICATIONS**

This application is a continuation of U.S. application Ser. No. 17/807,312 filed on Jun. 16, 2022 which is in turn a continuation of U.S. application Ser. No. 16/539,395 filed on Aug. 13, 2019 which claims benefit of U.S. provisional application Ser. No. 62/718,117 filed on Aug. 13, 2018. All documents above are incorporated herein in their entirety by reference.

FIELD OF THE INVENTION

The present invention relates to a cable spool. In particular, the present invention relates to a cable spool which is moveable between a first position and a second position. The cable spool is structurally configured for attaching to a surface such as a networking equipment and to support a plurality of fiber optic cables so as to enhance management of fiber optic-cables in high-density applications.

BACKGROUND TO THE INVENTION

To meet the demands of increasing density, fiber optic networking equipment such as cross connects have provided more or more ports for terminating more and more fiber optic cables. As the cables need to be periodically reconfigured or changed, the cables are typically loosely draped over a plurality of cable spools which are secured array-like in rows and columns to the racks adjacent the networking equipment or cross connect equipment and such that the cables can be readily accessed. One drawback of these existing designs is that with the increase in density and the number of cables being managed on a given array of cable spools, accessing and rerouting, removing or adding individual cables is difficult.

SUMMARY OF THE INVENTION

In order to address the above and other drawbacks, and in accordance with various aspects of the specification, there is provided a telescoping cable spool structurally configured for attaching to a networking equipment and to support a plurality of fiber optic cables. The cable spool comprises an attachment portion and a spool portion. The attachment portion is cylindrical. A fixed end of the attachment portion is structurally configured to be secured to a surface. The attachment portion comprises a free end opposite the fixed end. The attachment portion is arranged along an axis. The spool portion includes a pair of retaining portions interconnected by a support portion. The support portion is cylindrical. One of the retaining portions is positioned at each end of the support portion. The support portion defines a hollow. The hollow is dimensioned to fit over the attachment portion in a telescoping arrangement. The spool portion is configured to be moved relative to the attachment portion along the axis between a first retracted position and a second extended position. In the first retracted position the spool is positioned adjacent the surface. In the second extended position the spool portion is positioned away from the surface. In the second extended position the free end is positioned within the hollow. The telescoping cable spool enhances management of fiber optic-cables in high-density applications.

In some embodiments the telescoping cable further comprises a securing portion configured for securing the spool

2

portion in one of the first retracted position and the second extended position. In some embodiments the securing portion comprises an actuator, and wherein triggering the actuator releases the spool portion. In some embodiments, 5 when the spool portion is in the first retracted position, triggering the actuator releases the spool portion for movement to the second extended position. In some embodiments, when the spool portion is in the second extended position, triggering the actuator releases the spool portion for movement to the first retracted position. In some embodiments the actuator comprises a pushbutton at an outer end of the spool portion and wherein triggering the actuator comprises pressing the pushbutton. In some embodiments the pushbutton is configured for movement along the axis and positioned at least partially within the hollow and wherein when pressed the pushbutton moves axially into the hollow. In some embodiments the pushbutton is biased away from the hollow by a spring.

10 20 There is also provided a cable spool comprising spool structurally configured for attaching to a surface and to support a plurality of fiber optic cables to enhance management of fiber optic-cables in high-density applications. The cable spool comprises an attachment portion and a spool portion. A fixed end of the attachment portion is structurally configured to be secured to the surface. The attachment portion comprises a free end opposite the fixed end. The spool portion includes a pair of retaining portions interconnected by a support portion. One of the retaining portions is 15 positioned at each end of the support portion. The spool portion is configured to be slid relative to the attachment portion between a first retracted position and a second extended position. In the first retracted position the spool portion is positioned adjacent the surface. In the second extended position the spool portion is positioned away from the surface.

25 In some embodiments of the cable spool the spool portion is cylindrical. In some embodiments of the cable spool the spool portion defines a hollow dimensioned to receive the attachment portion. In some embodiments of the cable spool the attachment portion is cylindrical and the hollow dimensioned to receive the attachment portion in a telescoping arrangement. In some embodiments of the cable spool in the second extended position the free end is positioned within 30 the hollow.

35 40 Additionally, there is provided a cable spool structurally configured for attaching to a surface and to support a plurality of fiber optic cables so as to enhance management of fiber optic-cables in high-density applications. The cable spool comprises an attachment portion a spool portion. An inner end of the attachment portion is structurally configured to be fixed to the surface. An outer end of the attachment portion is structurally configured to be free standing. The spool portion is moveable relative to the attachment portion 45 between a first position and a second position.

50 In some embodiments of the cable spool the spool portion includes a pair of retaining portions interconnected by a support portion. In some embodiments of the cable spool the support portion is cylindrical. In some embodiments of the cable spool in the first position the spool portion is positioned adjacent the surface and in the second position the spool portion is positioned way from the surface. In some embodiments of the cable spool the spool portion defines a hollow dimensioned to receive the attachment portion. In 55 some embodiments of the cable spool the attachment portion is cylindrical and the hollow dimensioned to receive the attachment portion in a telescoping arrangement. In some

embodiments of the cable spool in the second extended position the free end is positioned within the hollow.

BRIEF DESCRIPTION OF THE DRAWINGS

FIG. 1 provides a front plan view of a cross connect system comprising a plurality of the telescoping cable spools in accordance with an illustrative embodiment of the present invention;

FIG. 2 provides a raised right perspective view of a telescoping cable spool in accordance with an illustrative embodiment of the present invention;

FIG. 3 provides an exploded view of a telescoping cable spool in accordance with an illustrative embodiment of the present invention;

FIG. 4A provides a raised right perspective view detailing the assembly of a telescoping cable spool in accordance with an illustrative embodiment of the present invention;

FIG. 4B provides a sectional view detailing the assembly of a telescoping cable spool along line IVB-IVB in FIG. 2;

FIG. 4C provides a sectional view detailing the assembly of a telescoping cable spool along line IVC-IVC in FIG. 2;

FIG. 4D provides a raised left rear exploded view detailing the assembly of a fixed part and a collar of a telescoping cable spool in accordance with an illustrative embodiment of the present invention;

FIG. 4E provides a raised left rear exploded view detailing the assembly of a telescoping cable spool in accordance with an illustrative embodiment of the present invention;

FIG. 4F provides a raised right rear view partially cut away view of an assembled telescoping cable spool in accordance with an illustrative embodiment of the present invention;

FIG. 5A provides a raised right rear view partially cut away view detailing the operation of a retracted assembled telescoping cable spool in accordance with an illustrative embodiment of the present invention;

FIG. 5B provides a raised right rear view partially cut away view detailing the operation of an extended assembled telescoping cable spool in accordance with an illustrative embodiment of the present invention;

FIG. 6 provides an exploded view of a telescoping cable spool in accordance with an alternative illustrative embodiment of the present invention;

FIG. 7A provides a raised right front perspective view of a telescoping cable spool in a retracted position and in accordance with an alternative illustrative embodiment of the present invention;

FIG. 7B provides a raised right front partially cut away view of a telescoping cable spool in an unlocked position and in accordance with an alternative illustrative embodiment of the present invention;

FIG. 7C provides a raised right front perspective view of a telescoping cable spool in an unlocked extended position and in accordance with an alternative illustrative embodiment of the present invention;

FIG. 7D provides a raised right front partially cut away view of a telescoping cable spool in a locked extended position and in accordance with an alternative illustrative embodiment of the present invention;

FIG. 8A provides a raised left front perspective view of a telescoping cable spool mounted to a networking equipment and in accordance with a second alternative illustrative embodiment of the present invention;

FIG. 8B provides a raised left front perspective view of the telescoping cable spool of FIG. 8A with a cable spool extended;

FIG. 8C provides a raised left front partially exploded perspective view of the telescoping cable spool of FIG. 8A;

FIG. 8D provides a detailed perspective view an inner surface of the extendable cable spool of FIG. 8A;

5 FIG. 9A provides a first detail cutaway view of the telescoping cable spool of FIG. 8A in a retracted position;

FIG. 9B provides a second detail cutaway view of the telescoping cable spool of FIG. 8A in an intermediate position;

10 FIG. 9C provides a third detail cutaway view of the telescoping cable spool of FIG. 8A in an extended position;

FIG. 10A provides a partially exploded view of the telescoping cable spool of FIG. 8A detailing the attachment to the networking equipment; and

15 FIG. 10B provides a sectional view along XB-XB in FIG. 8A.

DETAILED DESCRIPTION OF THE ILLUSTRATIVE EMBODIMENTS

Referring now to FIG. 1, a telescoping cable spool, generally referred to using the reference numeral 10, will be described. The spool 10 is foreseen for use together with a plurality of like spools 10 for example in a cross connect cabinet 12 comprising network equipment 14 and is used to support a plurality, or bundle, of fiber optic cables 16 for example terminated at one end at a respective port 18 of a respective piece of networking equipment 14. The bundles 20 of optic fibers 16 may be arranged in cable guides 20 and are shown as being looped over one or more of the spools 10 prior to the cables 14 exiting the cross connect cabinet 12, for example for termination at networking equipment in another cross connect cabinet (both not shown).

Referring now to FIG. 2, each spool 10 comprises a hollow outer housing or spool portion 22 moulded from a rigid material such as plastic or the like and comprising a pair of cable retaining flanges or retaining portions 24, 26 separated by a cylindrical cable support or support portion 28. As will be discussed in more detail below, a push button actuator or securing portion 30 is also provided.

Referring now to FIG. 3 in addition to FIG. 2, in addition to the hollow outer housing 22 and the push button actuator 30 the spool 10 further comprises a coil spring 32 mounted over the outer surface 34 of the push button actuator 30 and a hollow elongate cylindrical fixed part or attachment portion 36 comprising a pair of opposed attachment flanges 38 via which the fixed part 36 can be attached to a surface 40, for example using a pair of bolt 42 and nut 44 assemblies. The fixed part 36 is dimensioned to fit snugly within the cylindrical cable support 28 and to snugly receive the push button actuator 30. A collar 46 is also provided comprising a guide pin 48 which is dimensioned to fit within the fixed part 36 while encircling a narrow end 50 of the push button actuator 30. The guide pin 48 is arranged at right angles to an axis as defined by the collar 46 and such that a first end 52 of the guide pin 48 penetrates into the space 54 defined by the collar 46 and a second end 56 of the guide pin 48 extends outwards away from the collar 46. When assembled, 60 the first end 52 engages a first channel 58 in the narrow end 50 of the push button actuator 30 and the second end 56 engages inter alia a second channel 60 in the fixed part 36.

Referring now to FIG. 4A in addition to FIG. 3, in order to assemble the spool 10 prior to installation of the spool 10 onto a surface 40, the spring 32 is placed over the push button actuator 30 which is then rotated such that a pair of stops 62 align with respective ones of a pair of "J" shaped

guide channel openings 64. Alternatively the spring 32 can simply be inserted into the opening 66 in the retaining cable flange 24.

Referring now to FIG. 4B, the push button actuator 30 is then inserted into the opening 66 against the bias of the spring 32 such that the stops 62 are guided by respective ones of the guide channel 68 and until the stops 62 butt against respective edges 70 of the guide channels 68. At this point the spring 32 is compressed between the actuator 30 and an annular partial collar 72 which is positioned within the cylindrical cable support 28. Referring now to FIG. 4C in addition to FIG. 4B, the actuator 30 is rotated 90 degrees clockwise and until the stops 62 are aligned with respective ends 74 of the guide channels 68 and then released. The spring 32 biases the actuator 30 axially away from the annular partial collar 72 and such that the stops 62 rest against their respective ends 74 of the guide channels 68.

Referring now to FIG. 4D, the collar 46 is then assembled to the fixed part 36 by aligning the first end 52 of the guide pin 48 with an entrance 76 to the second channel 60, sliding the collar into the fixed part 36 then rotating the collar 46 about 30 degrees clockwise until the guide pin 48 is aligned with one of the flanges 38, as shown in FIG. 4E.

Still referring to FIG. 4E, the fixed part 36/collar 46 assembly is assembled to the cylindrical cable support 28/actuator 30 assembly by aligning a rail 78 with a channel 80 on the inner surface of the cylindrical cable support 28 and then inserting the fixed part 36/collar 46 assembly into the housing 22 via an opening 82 in the flange 26 until the attachment flanges 38 are received within corresponding attachment flange receiving cut outs 84 in the flange 26, the collar 42 encircles the narrow end 50 of the actuator 30, and the first end 52 of the guide pin 48 is received within the first channel 58 in the narrow end 50 of the push button actuator 30. At this point the second end 54 of the guide pin 48 is engaged within the second channel 60 in the fixed part 36 as well as an annular groove (not shown).

Referring now to FIG. 4F in addition to FIG. 3, to complete the assembly the collar 46 is rotated clockwise about 30 degrees. In this regard an annular channel 86 is provided on the inner surface 88 of the housing 20 into which the second end 56 of the guide pin 48 extends and within which the second end 56 of the guide pin 48 can travel radially.

Referring to FIG. 5A in addition to FIGS. 3 and 4F, the principle of operation of an assembled spool 10 will now be described. Due to the annular channel 86 in the housing the collar 46 is able to rotate relative to the housing 22 but otherwise must move with the housing 22 longitudinally along the axis of the spool 10. Pressing the actuator 30 imparts a rotational force to the collar 46 via the first end 52 of the guide pin 48 and the first channel 58 in the narrow end 50 of the push button actuator 30. In this regard, the portion of the channel 58 within which the first end 52 of the guide pin 48 moves is at an angle to the longitudinal axis of the spool 10. The angle is chosen such that movement of the push button actuator 30 relative to the housing 22 (and therefore the collar 46) between an unactuated and an actuated position imparts sufficient rotation to the collar 46 such that the second end 56 of the guide pin 48 is brought into alignment with a longitudinal part 90 of the second channel 60 in the fixed part 36.

Referring to FIG. 5B in addition to FIG. 3, the housing 22 is now free to telescope vis-a-vis the fixed part 36 and such that the housing 22 can be extended. Once extended, release of the actuator 30 allows the actuator 30 to return to its non-actuated position relative to the housing 22 via the

biasing force of the spring 32. A reverse rotational force is imparted on the collar 46 through the interaction of the first end 52 of the guide pin 48 and the angled section of the first channel 58 and such that the second end 56 of the guide pin 48 travels into an closed end 92 of the second channel 60, thereby locking the housing 22 in its extended position. A person of ordinary skill in the art will now understand that the housing 22 can be replaced in its non-extended position by pushing the actuator 30 while moving the housing 22 into its non-extended position and then releasing the actuator 30.

Referring now to FIG. 6, in an alternative embodiment the spool 10 is comprised of a housing 22 comprising a hollow cylindrical cable support 28, an actuator 30, a spring 32 and a fixed part 36. As will be discussed in more detail below a guide pin 48, manufactured from steel or the like, is also provided.

Still referring to FIG. 6, in order to assemble the alternative embodiment of the spool 10 prior to installation of the spool 10 onto a surface 40, the spring 32 is placed over the push button actuator 30 and inserted into the opening 66 until the spring is compressed between the actuator 30 and an annular partial collar 72 which is positioned within the cylindrical cable support 28. Alternatively the spring 32 can simply be inserted into the opening 66 in the retaining cable flange 24. The fixed part 36 is then inserted into the housing 22 until the attachment flanges 38 are received in corresponding cut-outs (not shown) in the rearward cable retaining flange 26. In this regard, the inner surface (not shown) of the cylindrical cable support 28 matches a pair of opposed flat surfaces 94 such that the fixed part 36 is oriented correctly vis-a-vis the housing 22. A guide pin receiving bore 96 in the actuator 30 is aligned with a guide slot 98 in the cylindrical cable support 28 and the guide pin 48 inserted into the bore 96 and via the guide channel 100 in the fixed part 36.

Referring to FIG. 7A, in an un-actuated state the guide pin 48 is held against a first end 102 of the guide slot 98 in the cylindrical cable support 28 by the spring 32. Referring to FIG. 7B in addition to FIG. 7A, by pressing the actuator 30 the guide pin 48 is moved within the guide slot 98 towards a second end 104 thereof while imparting a rotation to the actuator 30. The guide pin 49 also travels within a first angled guide channel part 106 of the guide channel 100 until it is aligned with a longitudinal guide channel part 108. With reference to FIG. 7C in addition to FIG. 7B, at this point the housing 22 can be telescoped relative to the fixed part 36 until the guide pin 48 reaches a second angled guide channel part 110. Subsequent release of the actuator 30 allows the actuator 30 to move relative to the housing 22 via the biasing force of the spring 32. The guide pin 48 moves into the second angled guide channel part 110, thereby imparting a rotation to the actuator, and while the guide pin 48 simultaneously returns to the first end 102 of the guide slot 98, thereby locking the housing 22 in its extended position. A person of ordinary skill in the art will now understand that the housing 22 can be replaced in its non-extended position by pushing the actuator 30 while moving the housing 22 into its non-extended position and then releasing the actuator 30.

Referring now to FIG. 8A, in an alternative embodiment, the cable spool 10 is separated into a static cable spool 112 and an extendable cable spool 114. The static cable spool 112 is illustratively slideably mounted to an elongate rail 116 which is in turn secured horizontally between the vertical supports 118 of a cross connect cabinet 120 or the like. A tray 122 is illustratively provided behind the vertical supports 118 for receiving one or more optical cables (not shown) or the like. Additionally, a cable guide 124 is

provided between the static cable spool 112 and the tray 122 via which the one or more cables may transit between the static cable spool 112 and the tray 122. A vertical guide 126 is provided on either side of the cable guide 124 to ensure a smooth transition between the tray 122 and the static cable spool 112. The static cable spool 112 further comprises a cable retaining flange 128 separated from the aperture 124 by a cylindrical cable support 130. Similarly, the extendable cable spool 114 comprises an inner and outer pair of cable retaining flanges, respectively 132, 134, separated from one another by a cylindrical cable support 136.

Still referring to FIG. 8A, as will be discussed in more detail below, a release button 138 is provided which disengages a rail locking mechanism (not shown) which comprises inter alia a serrated cut-out 140 in the elongate rail 116. Releasing the rail locking mechanism allows the assembly of the static cable spool 112 to be slid along the elongate rail 116 and such that the assembly comprising the static cable spool 112 and the extendable cable spool 114 may be moved horizontally in a direction at right angles to the spool axis A of the cable spool 10.

Referring now to FIG. 8B in addition to FIG. 8A, as will be discussed in more detail below, the extendable cable spool 114 is secured in place by a mechanism (not shown) which can be released by pressing a push button actuator 142 while for example pulling on the outer cable flange 134.

Referring now to FIG. 8C, the extendable cable spool 114 is illustratively comprised of upper and lower opposed halves, respectively 144, 146. The halves 144, 146 are secured together about the push button actuator 142 and a cylindrical fixed part 148 extending from the cable retaining flange 128 of the static cable spool 112 and along which the assembled halves 144, 146 may slide. In this regard, the halves 144, 146 are secured together to form the extendable cable spool 114 via fasteners illustratively comprising self-tapping screws 150 and interlocking flexible tabs 152 or the like. A spring 154 is provided to bias the pushbutton actuator 142 outwards along the axis A of the cable spool 10. The pushbutton actuator 142 comprises a pair of guide pins 156 that move within respective slots 158 in the cylindrical fixed part 148 thereby limiting the travel of the pushbutton actuator 142 relative to the cylindrical fixed part 148 between a retracted position and an extended position. In this regard, each slot 158 comprises a rearward guide pin receiving angled slot 160 and a forward guide pin receiving angled slot 162 at either end thereof. As will be discussed below, each guide pin 156 rests in one of the guide pin receiving angle slots 160, 162 when the extendable cable spool 114 is in one of the retracted position or extended position.

Referring to 8D in addition to FIG. 8C, the end of each guide pin 156 engages respective ones of a pair of elongate recesses 164 positioned on an inner surface 166 of a respective one of the upper and lower opposed halves 144, 146. The pair of recesses 164 interlink the guide pins 156 with their respective opposed halves 144, 146 such that when assembled the pushbutton actuator 142 and the extendable cable spool 114 move together when the extendable cable spool 114 is moved between the retracted position and the extended position.

Referring now to FIG. 9A, in a first retracted position of the extendable cable spool 114, as discussed above, when in the retracted position the guide pins 156 are engaged in respective ones of the rearward guide pin receiving angles 160. As will now be understood by a person of ordinary skill in the art, and with additional reference to FIG. 8C, the spring 154 biases the pushbutton actuator 142 relative to the

cable spool 114 and such that the end of each guide pin 156 is biased normally towards a front of their respective elongate recesses 164. Moving the pushbutton actuator 142 against the bias of the spring 154 introduces a small rotational movement to the pushbutton actuator 142 relative to the cable spool 114 as the end of the guide pin 156 travels along the elongate recess 164 which in turn moves the guide pin 156 out of the rearward guide pin receiving angled slot 160 and into the elongate slot 158 such that the cable spool 114 can be extended. On release of the pushbutton actuator 142 when the cable spool 114 is in the retracted position, the biasing ensures that the ends of the guide pins 156 move forward along the recess 164 and such that guide pins 156 are moved into and held securely in their respective rearward angled slot 160. A similar effect is achieved when the cable spool 114 is in the extended position, and the guide pins 156 are moved under bias of the spring 154 into their respective forward guide pin receiving angled slot 162.

Referring to FIG. 9B, and in light of the discussion above, the guide pins 156 are moved out of their respective rearward guide pin receiving angles 160 by pushing the pushbutton actuator 142 against the bias of the spring 154 (reference 154 in FIG. 8D). In this manner, the guide pin 156 is moved out of the rearward guide pin receiving angled slot 160 and into the slot 158.

Referring now to FIG. 9C, once the guide pin has been actuated into the slot 158 the extendable cable spool 114 can be moved into the extended position where the guide pin 156 comes to rest in the forward guide pin receiving angled slot 162.

Referring now to FIG. 10A, static cable spool 112 comprises a front cable spool part 164 which is snap fit to a rear cable spool part 166 about the elongate rail 116 which fits within an aperture formed by cut outs 168, 170 and such that the horizontal rail 116 slides therein. The rear cable spool part 166 comprises flexible tabs 172 which engage with corresponding features on the front cable spool part 164 to secure the two pieces together. Screws (not shown) are also provided. The elongate rail 116 is securable to the vertical supports 118 of a cross connect cabinet 120 by a pair of bolts 174 which are inserted through respective ones of a pair of cut 176 outs in the elongate rail 116. Similarly, the cable guide 124 is secured to the rear cable spool part 166 by a pair of bosses 178 which engage with respective indentations (not shown) on a rearward side of the rear cable spool part 166.

Referring now to FIG. 10B in addition to FIG. 10A, as discussed above a release button 138 is provided which releases a mechanism such that the cable spool 10 may slide horizontally along the elongate rail 116. The mechanism comprises a stop 180 which is connected to the release button 138 by a relative narrow collar 182. The serrated cut-out 140 defines plurality of stop receiving spaces 184 arranged side by side in a line along said elongate rail 116. Each stop receiving space 184 is separated from adjacent stop receiving spaces 184 by a relatively narrow gap 186 which are defined by pairs of opposed teeth 188, 190. The mechanism further comprises a pair of flexible arms 192 which are held within recesses 194 in the rear cable spool part 166 and which serve to bias the stop 180 and the release button 138 against an actuating force. Pressing the release button 138 brings the collar 182 into alignment with the gaps 186. As the dimensions of the collar 182 are such that the collar 182 may pass freely through each gap 186, the cable spool 10 is free to slide along the elongate rail 116. On release of the release button 138 the flexible arms 188 bias the stop 180 towards the stop receiving spaces 184 and such

the stop 180 will move into an aligned one of the stop receiving spaces 184, thereby preventing the cable spool 10 from sliding along the elongate rail 116.

Although the present invention has been described hereinabove by way of specific embodiments thereof, it can be modified, without departing from the spirit and nature of the subject invention as defined in the appended claims.

The invention claimed is:

1. A telescoping cable spool structurally configured for attaching to a networking equipment and to support a plurality of fiber optic cables comprising:
  - an attachment portion;
  - a spool portion;
  - wherein the attachment portion is cylindrical;
  - wherein a fixed end of the attachment portion is structurally configured to be secured to a surface;
  - wherein the attachment portion comprises a free end opposite the fixed end;
  - wherein the attachment portion is arranged along an axis;
  - wherein the spool portion includes a pair of retaining portions interconnected by a support portion;
  - wherein the support portion is cylindrical;
  - wherein one of the retaining portions is positioned at each end of the support portion;
  - wherein the support portion defines a hollow;
  - wherein the hollow is dimensioned to fit over the attachment portion in a telescoping arrangement;
  - wherein the spool portion is configured to be moved relative to the attachment portion along the axis between a first retracted position and a second extended position;
  - wherein in the first retracted position the spool is positioned adjacent the surface;
  - wherein in the second extended position the spool portion is positioned away from the surface; and
  - wherein in the second extended position the free end is positioned within the hollow so as to enhance management of fiber optic-cables in high-density applications.
2. The telescoping cable spool of claim 1, further comprising a securing portion configured for securing the spool portion in one of the first retracted position and the second extended position.
3. The telescoping cable spool of claim 2, wherein the securing portion comprises an actuator, and wherein triggering the actuator releases the spool portion.
4. The telescoping cable spool of claim 3, wherein when the spool portion is in the first retracted position, triggering the actuator releases the spool portion for movement to the second extended position.
5. The telescoping cable spool of claim 3, wherein when the spool portion is in the second extended position, triggering the actuator releases the spool portion for movement to the first retracted position.
6. The telescoping cable spool of claim 3, wherein the actuator comprises a pushbutton at an outer end of the spool portion and wherein triggering the actuator comprises pressing the pushbutton.
7. The telescoping cable spool of claim 6, wherein the pushbutton is configured for movement along the axis and positioned at least partially within the hollow and wherein when pressed the pushbutton moves axially into the hollow.
8. The telescoping cable spool of claim 7, wherein the pushbutton is biased away from the hollow by a spring.

9. A cable spool structurally configured for attaching to a surface and to support a plurality of fiber optic cables comprising:

- an attachment portion;
- a spool portion;
- wherein a fixed end of the attachment portion is structurally configured to be secured to the surface;
- wherein the attachment portion comprises a free end opposite the fixed end;
- wherein the spool portion includes a pair of retaining portions interconnected by a support portion;
- wherein one of the retaining portions is positioned at each end of the support portion;
- wherein the spool portion is configured to be slid relative to the attachment portion between a first retracted position and a second extended position;
- wherein in the first retracted position the spool portion is positioned adjacent the surface; and
- wherein in the second extended position the spool portion is positioned away from the surface so as to enhance management of fiber optic-cables in high-density applications.

10. The cable spool of claim 9, wherein the spool portion is cylindrical.

11. The cable spool of claim 9, wherein the spool portion defines a hollow dimensioned to receive the attachment portion.

12. The cable spool of claim 10, wherein the attachment portion is cylindrical and the hollow dimensioned to receive the attachment portion in a telescoping arrangement.

13. The cable spool of claim 10, wherein in the second extended position the free end is positioned within the hollow.

14. A cable spool structurally configured for attaching to a surface and to support a plurality of fiber optic cables comprising:

- an attachment portion;
- a spool portion;
- wherein an inner end of the attachment portion is structurally configured to be fixed to the surface;
- wherein an outer end of the attachment portion is structurally configured to be free standing; and
- wherein the spool portion is moveable relative to the attachment portion between a first position and a second position so as to enhance management of fiber optic-cables in high-density applications.

15. The cable spool of claim 14, wherein the spool portion includes a pair of retaining portions interconnected by a support portion.

16. The cable spool of claim 15, wherein the support portion is cylindrical.

17. The cable spool of claim 14, wherein in the first position the spool portion is positioned adjacent the surface and in the second position the spool portion is positioned away from the surface.

18. The cable spool of claim 14, wherein the spool portion defines a hollow dimensioned to receive the attachment portion.

19. The cable spool of claim 18, wherein the attachment portion is cylindrical and the hollow dimensioned to receive the attachment portion in a telescoping arrangement.

20. The cable spool of claim 19, wherein in the second extended position the free end is positioned within the hollow.
